UNITED STATES PATENT OFFICE

137,699

DESIGN FOR A JABOT OR SIMILAR ARTICLE

Sylvan M. Baar, New York, N. Y.

Application March 18, 1944, Serial No. 112,948

Term of patent 3½ years

(Cl. D3—32)

To all whom it may concern:

Be it known that I, Sylvan M. Baar, a citizen of the United States of America, residing in the city of New York, county of New York, and State of New York, have invented a new, original, and ornamental Design for a Jabot or Similar Article, of which the following is a specification, reference being had to the accompanying drawing, forming part thereof.

Fig. 1 is a plan view of a jabot or similar article showing my new design.

Fig. 2 is an edge view thereof.

I claim:

The ornamental design for a jabot or similar article, substantially as shown.

SYLVAN M. BAAR.
